UNITED STATES PATENT OFFICE.

DANIEL GREEN SAUNDERS, JR., OF KANSAS CITY, MISSOURI, ASSIGNOR, BY MESNE ASSIGNMENTS, TO THE SAUNDERS SEALER COMPANY, OF CLEVELAND, OHIO, A CORPORATION.

ENVELOP MOISTENER AND SEALER.

1,034,933.

Specification of Letters Patent. Patented Aug. 6, 1912.

Application filed July 2, 1908. Serial No. 441,530.

To all whom it may concern:

Be it known that I, DANIEL GREEN SAUNDERS, Jr., a citizen of the United States, residing at Kansas City, Missouri, have invented certain new and useful Improvements in Envelop Moisteners and Sealers, of which the following, taken in connection with the drawing, is a description.

My invention has for its object the production of a device for moistening and sealing down the flaps of envelopes, one that is small in size so that it occupies very little room upon a desk, and is always ready for use.

My device is very simple in construction, cheap to manufacture and effectual in its operation.

In the accompanying drawings forming part of this specification, and in which like letters of reference indicate corresponding parts I have illustrated one form of device embodying the essential features of my invention, although the same may be carried into effect in other ways without in the least departing from the spirit of my invention, and in these drawings Figure 1 is a perspective view of my invention illustrating the device when in use; Fig. 2 is a sectional view taken through the center of the device, and Fig. 3 is a transverse sectional view taken on line 3—3 of Fig. 2.

In carrying out my invention A represents the base or standard of my device having a foot a adapted to hold the sealer in upright position. Extending forwardly from this base is a trough A' into which is placed a moistening pad A² which may be of felt or any other suitable absorbent material.

Extending upwardly from the base at an angle of 45 degrees more or less is a cylinder B, which is provided with an inwardly extending circumferential shoulder b. This cylinder is soldered or otherwise secured to the base A, and has a small opening b' from said cylinder to the trough A². Fitting inside of the cylinder B is a tube or reservoir B' which has a small aperture b² at the lower end thereof. When in use this tube B contains the moistening liquid for the envelopes. A cap B² fits over the end of the cylinder B and is provided with an annular opening b³. This cap may be screw threaded upon the cylinder or held thereon by frictional contact as desired. An elongated opening c is provided in the cylinder B, for a purpose hereinafter described.

A sealing bar C extends parallel with the moistening pad A, the center of one side thereof extending upwardly to the cylinder B and is clamped around said cylinder and held in position by the clamping ring C'.

Inwardly extending lugs c', c engage with the slot c to prevent said clamp from moving sidewise. The forward edge of the sealing bar is slightly curved to extend over the edge of the trough A' and is then curved upwardly as shown to form the means for sealing the envelop. Each end of the sealing bar C is bent in an upward curve to form a guide for the envelop flap as it is about to be inserted beneath said bar to be moistened.

When the device is to be used the tube B' is filled with water and the pad A² saturated, the sealing bar adjusted to approximately the position shown in Fig. 2 when the flap d of the envelop D may be inserted between the sealing bar and moistening pad. After the envelop is inserted to the position shown in Fig. 1 the operator presses forward on the cylinder B, which serves as a handle in the use of the device, and gradually pulls the moistener away from the flap, at the same time sealing the flap to the envelop. After the envelops have been moistened and sealed the sealing bar C may be removed from the device by loosening the clamping ring C' and the moistening pad A² used for moistening the stamps to be attached.

The advantages of my invention will be apparent to those skilled in the art. My improvements are very simple in construction, comprise few parts, can be easily and cheaply manufactured and placed in position and does the work of a large machine.

I claim:

1. In an envelop moistener and sealer, the combination, with a reservoir handle, of a base made of a single sheet of metal and bent to form a transverse trough at the front and then continuing integrally beneath the handle and secured to it and then turned down to make a foot, a wick in said trough, and a pressing device carried by the handle and overhanging the wick.
2. In an envelop moistening and sealing

device, the combination of a trough, a handle connected therewith, a T-shaped sheet metal presser plate overhanging the trough and provided with a concaved upwardly extending shank adapted to lie alongside of the handle, the handle and shank being provided with a coöperating projection and depression to position the shank, and a clamping ring surrounding the handle and adapt-

ed to embrace said shank to removably hold to the presser plate thereto.

In testimony whereof I have signed this specification in the presence of two subscribing witnesses.

DANIEL GREEN SAUNDERS, JR.
